STORM SASH AND SCREEN ASSEMBLY

Vincent Van Fleet, Detroit, Mich.

Application October 21, 1944, Serial No. 559,674

9 Claims. (Cl. 160—90)

1

This invention relates to an improved storm sash and screen assembly.

An object is to provide an improved storm sash and screen assembly which is of light weight, inexpensive construction, and which may be attached within a window opening and left permanently in place therein throughout the year.

Another object is to provide an improved storm sash assembly of the character described which includes in addition to two slidable storm sash adapted to form a complete covering for the window opening, a screen sash which may be lowered when desired to cover the lower portion of the window opening normally occupied by one of the storm sash and such storm sash may be raised opposite the other storm sash over the upper half of the window opening.

Another object is to provide an assembly of the character set forth wherein each of the several sashes may be independently removed for repair or replacement.

Another object is to provide an assembly of the character set forth wherein the sash carrying frame of the assembly is formed of sheet metal in such a manner as to provide a frame of light weight which possesses the strength and rigidity necessary to serve its purpose and which frame is adaptable within limits to fit window openings which vary slightly in size.

A further object is to provide a structure of the character described wherein a supplemental sill member is provided which superposes the permanent sill portion of the rectangular frame unit and which supplemental sill is removable and replaceable with other sill members.

A further object is to provide an assembly as set forth wherein a storm sash is formed of sheet metal in such a manner that a window pane may be readily placed therein or removed therefrom.

A further object is to provide in an assembly of the character described sashes so constructed that the sill of one sash is provided with a projecting ledge which bears against the header of another sash to form a tight joint therebetween.

Another object is to provide a sash formed of sheet metal the inner face of which is shaped to exhibit a projecting ledge which serves as a handle to raise the sash.

Another object is to provide a screen sash structure formed of sheet metal wherein the screen may be readily installed or replaced.

Other objects, advantages and meritorious features will more fully appear from the following description, accompanying drawings and appended claims wherein:

2

Figure 1 is a fragmentary elevation showing my improvement in place in a window opening.

Figure 2 is a horizontal sectional view taken on line 2—2 of Figure 1.

Figure 3 is a vertical sectional view taken on line 3—3 of Figure 1.

Figure 4 is an enlarged cross sectional view through one jamb portion of the assembly frame taken on the same line as Figure 2.

Figure 5 is a view taken on the line 5—5 of Figure 3.

Figure 6 is a view taken on the line 6—6 of Figure 5.

Figure 7 is a view taken on the line 7—7 of Figure 3 showing the structure partly broken away.

Figure 8 is a cross sectional view taken through the bottom rail of a storm sash showing a modification as compared with Figure 3 and 4.

Figure 9 is a view taken on the same line as Figure 8 showing a bottom rail of a storm sash of a cross section similar to Figure 4.

Heretofore it has been the practice to provide storm sash and screens for windows of separate assemblies. The storm sash are removed when the screens are placed on the windows and vice versa. The purpose of this invention is to provide a storm sash and screen assembly which may be secured permanently in place and which includes two storm sash adapted to furnish a complete storm window coverage for the window opening in the winter but one of which storm sash may be elevated and the screen lowered to fill the openings left by the upraised storm sash.

In the several figures of the drawings conventional vertically slidable windows are indicated at 10 and 12. These windows are mounted for vertical slidable movement between jamb parts 16 and an inner window stop 18, parting stop 20 and outer stop 22 as shown particularly in Figures 2 and 3. The window sill is indicated as 24 in Figure 3 and the header as 26. The outer upright casing frame is indicated as 28 and the header member as 29. The above structure is conventional and forms no part of the invention except as the associative environment for my storm sash and screen assembly.

The invention resides in providing a storm sash and screen assembly of the character herein-after described. It comprises a unitary frame-work which is of a generally rectangular shape to fit a window opening as shown in Figure 1 and such assembly is there indicated as 30. This frame may be formed of sheet metal bent to the shape shown in Figures 2 and 3. Figure 2 shows the shape of the upright or jamb portions of the

frame and Figure 3 shows the shape of the header and sill portions of the frame. The sheet metal is bent to form an outer face plate 32 which may be attached by screws 34 to the window casing header or upright members. In cross section the jamb portions and header portions are similar and exhibit a storm and screen sash engaging portion 38 disposed at a right angle to the portion 32 which portion 38 is shaped to define three sash guide channels indicated as 34, 36 and 38 in both Figures 2 and 3.

The metal is so shaped in the formation of these guide channels as to provide folded side wall portions or what might be termed lands 40. An outer storm sash 42 is supported for slidable movement within the guide channel 34 and an inner storm sash 44 is supported for slidable movement within the guide channel 36 and a screen sash 46 is supported for slidable movement within the guide channel 38, all as shown in Figures 2 and 3. Each sash covers approximately one half of the window opening.

These sliding sash elements are provided upon one vertical stile with a pair of springs 48 which ride within the channel and hold the sash snugly toward one side of the frame. Upon compression of the springs the removal of the sashes from the sash guide channels may be readily accomplished as will be apparent from Figure 7. The bottom of the guide channel wherein the springs travel is provided with a detent or projection 50 over which one of the springs may seat so as to hold the sash in a determined elevated position. The spring will yield however upon downward pressure being exerted on the sash to lower the sash to permit such lowering.

The two storm sash may be disposed as shown in Figure 3 with the screen sash elevated. On the other hand, the inner storm sash 44 may be raised and the screen lowered. The assembly therefore serves both as a storm sash and screen assembly for both summer and winter use. Ordinarily blinds within the house are drawn half way down so the upraised screen or inner upraised storm sash will not be objectionable.

The bottom portion of the frame assembly 30 is indicated in Figure 3 as 52. It is shaped to seat upon the sloping sill 24. To facilitate removal of the storm sash and washing of the window opening sill there is provided a removable sill member 54 shown in Figures 3 and 6 which seats upon the sill portion 52 of the integral rectangular frame. This sill member 54 is channel shaped in cross section with the bottom portion of the channel disposed upwardly and slightly deformed to provide beads 56 which form parting stops between the sash. The member 54 is cut out at the ends to seat over the side walls or lands 40 that separate the sash guide channels 34, 36 and 38 of the jamb portions of the frame structure. Between these cut outs there are projecting tongues 58 which are received within the channels 34, 36 and 38 of the jamb portions of the framework.

A separable inner face plate 60 is provided which is secured by screws or the like to the outer stop as shown in Figure 2 and which closes the space between the outer stop and the channel jamb portion of the frame as shown in Figure 2. This strip 60 is adjustable with respect to the side wall of the innermost channel so that regardless of variation in window width within certain limits this space will be closed.

The storm sash which carries the glass panes 62 may have a cross sectional shape such as is

shown in Figures 2, 3 and 4. Each storm sash is of a generally rectangular shape and in cross section it is bent up out of sheet metal so as to provide an outer tubular portion 64. One portion of the strip which is bent up to form the tube 64 extends up as a lip 66 over the glass pane and is rolled over at the edge and bears thereagainst as illustrated particularly in Figure 4. The other margin of the strip is folded over upon itself as at 68 underneath the edge of the glass 62 and a spline member 70 shaped as shown in Figure 4 has one angular leg 69 (Figure 4) that is received underneath the fold 68 to hold the spline in place.

The spline is angular in cross section and is formed of resilient material and the other angular leg portion 71 (Figure 4) of the spline is shaped to engage the glass pane as shown in Figure 4. Another form of spline is shown in Figure 8. This spline which is indicated as 12 has a portion 14 which is received within a channel 16 of the sash frame underneath the edge of the glass. The spline has an upper leg portion however which bears against the face of the glass and holds it against the upstanding lip 78 of the frame member. The upstanding lip 78 of this frame member corresponds to the lip 66 of the frame member shown in Figure 4.

The frame member shown in Figure 8, as also the frame member shown in Figure 9, is the lower frame member of the sash and the inner face portion is bent to provide a projecting ledge 80 which is spaced above the bottom edge of the sash frame and serves as a handle which may be grasped to raise or lower the sash. This portion 80 is of a length to extend between the side walls 40 of the guide channels in the jamb portion of the frame. It projects inwardly such a distance that when its sash frame is elevated it will bear against the top frame of the adjacent inner sash as shown in Figure 3 where the portion 80 on the sill of the outer storm sash is shown as bearing against the top frame member of the inner storm sash. In the same manner portion 80 of the inner storm sash would bear against the top frame member of the screen sash when the screen was lowered and the inner storm sash was raised.

Figure 9 is an enlarged cross section of the structure shown in Figure 2 and is provided with the projecting portion 80 and the spline 70 as shown in Figures 2 and 4.

The screen sash is shown in enlarged cross section in Figure 4. It is of generally rectangular shape. There is an outer tubular portion 90 and an inner channel-shaped portion 92. The channel-shaped portion lies within the same plane of the sash as the tubular portion 90 and is open on one side. Screen wire 94 is stretched over the sash opening and turned into the channel 92. It will be seen that the channel 92 has a greater width at the bottom than at the open side. A channel-shaped spline 96 is provided. The side wall of this channel spline diverge toward the open side so that when the spline is received within the channel 92 over the screen wire it will hold the screen wire securely in place. The side walls of this channel spline 96 are resilient.

What I claim is:

1. A storm sash and screen assembly comprising a generally rectangular sash carrying frame adapted to be secured within a window opening having an outer stop and an outer casing, the two opposed jamb portions of the frame exhibiting sash engaging jamb faces each provided with three parallel closely adjacent upright sash guide

channels, a storm sash slidably supported for raising and lowering in each of two of said guide channels, a screen sash slidably supported for raising and lowering in the third of said guide channels, each upright jamb portion of the frame having an outer face extending at a right angle to the sash engaging jamb face and adapted to overlap and be secured to the outer casing about the window opening within which the frame is disposed supporting the sash engaging jamb portion of the frame spaced from the outer window stop.

2. A storm sash and screen assembly comprising a sash carrying frame of generally rectangular shape and including opposed upright jamb portions connected at the top by a header portion and connected at the bottom by a sill portion forming a unitary frame structure, the opposed upright jamb portions exhibiting sash engaging jamb faces each defining three parallel closely adjacent upright sash guide channels, and a supplemental sill member received within the framework superposing the sill portion of the framework, said supplemental sill member being cut out at the ends to seat over the side walls of the guide channels and to extend into said channels.

3. A storm sash and screen assembly comprising a sash carrying frame of generally rectangular shape adapted to be secured within a window opening provided with an outer stop and an outer casing, said frame including opposed upright jamb portions connected at the top by a header portion and connected at the bottom by a sill portion forming a unitary frame structure, the opposed upright jamb portions exhibiting sash engaging jamb faces each defining three parallel closely adjacent upright sash guide channels, each upright jamb portion and the header portion being right angular in sectional outline and exhibiting an outer face disposed at right angles to the sash engaging jamb face and adapted to overlap and be secured to the casing about the window opening within which said frame is disposed to support said frame within the window opening and supporting the sash engaging jamb portion of the frame spaced inwardly from the outer window stop and the outer window casing, and means closing the space between said outer stop and the sash engaging jamb portion of the frame.

4. A storm sash and screen assembly comprising a sash carrying frame of generally rectangular shape and including opposed upright jamb portions connected at the top by a header portion and connected at the bottom by a sill portion forming a unitary frame structure, the opposed upright jamb portions exhibiting sash engaging jamb faces each defining three parallel closely adjacent upright sash guide channels, each upright jamb portion and the header portion being right angular in sectional outline and exhibiting an outer face disposed at right angles to the sash engaging jamb face, said frame adapted to be disposed within a window opening having a casing thereabout and provided with an outer window stop, said outer face adapted to overlap and be secured to the casing about the window opening within which the frame is disposed and supporting the sash engaging jamb face in spaced relation to the outer window stop, and a separate inner jamb face plate secured to said stop and overlapping the inner edge of the sash engaging jamb face plate.

5. A storm sash and screen assembly comprising a sash carrying frame of generally rectangu-

lar shape and including opposed upright jamb portions connected at the top by a header portion and connected at the bottom by a sill portion forming a unitary frame structure, the opposed upright jamb portions exhibiting sash engaging jamb faces each defining three parallel closely adjacent upright sash guide channels, each upright jamb portion and the header portion being right angular in sectional outline and exhibiting an outer face disposed at right angles to the sash engaging jamb face, said frame adapted to be disposed within a window opening having a casing thereabout and provided with an outer window stop, said outer face adapted to overlap and be secured to the casing about the window opening within which the frame is disposed to support the sash engaging jamb face in spaced relation to the outer window stop, and a separate inner jamb face plate secured to said stop and overlapping the inner edge of the sash engaging jamb face plate and a supplemental sill member removably received within the frame superimposing the sill portion of the frame, said supplemental sill member being cut out at the ends to seat over the side walls of the guide channels of the sash engaging jamb faces and having portions adapted to extend into said channels.

6. A storm sash and screen assembly comprising a sash carrying frame of generally rectangular shape and including opposed upright jamb portions connected at the top by a header portion and connected at the bottom by a sill portion forming a unitary frame structure, the opposed upright jamb portions exhibiting sash engaging jamb faces each defining three parallel closely adjacent upright sash guide channels, a storm sash slidably supported for raising and lowering in each of the two outer guide channels, a screen sash slidably supported for raising and lowering in the innermost of said guide channels, each of said two storm sashes having a bottom rail provided with a ledge projecting inwardly between and over the inner side wall of the sash guide channel within which the sash travels, said ledge having a width equal to the thickness of said side wall.

7. A frame sash and screen assembly comprising a generally rectangular framework adapted to be secured within a window opening, the opposite upright jamb members of the framework defining three upright parallel closely adjacent guide channels all lying in a plane normal to that of the opening, a storm sash slidably supported in each of two sash guide channels, a screen sash slidably supported within the third sash guide channel, the side walls of the intermediate guide channel separating the vertical sash members of the intermediately positioned sash member from the two outer sash members, each sash being supported for raising and lowering, the two storm sash adapted to be disclosed opposite one another in the upper half of the window opening and to be disposed one in the upper half and the other in the lower half of the window opening to close completely the window opening, the screen sash adapted to be disposed either within the upper half of the window opening or within the lower half thereof, the transverse rail of one of said sashes being provided with a lip projecting toward an adjacent sash and across the side wall of the intermediate guide channel between said sashes to close the space between said rail and a transverse rail of said adjacent sash.

8. A sash assembly for a window opening comprising a frame structure having a pair of opposed upright jamb members each defining three upright parallel adjacent guide channels all lying in a plane normal to that of the window, the intermediate guide channel being separated from each of the two outer guide channels by a guide channel wall, a sash structure mounted within each guide channel for slidable movement therethrough, each of two of said sliding sash members having a horizontal rail provided with a linear lip extending lengthwise thereof and projecting across a side wall of an intermediate sash guide toward the sash member in the adjacent guide channel to engage a horizontal rail

10

members having a horizontal rail provided with a linear lip extending lengthwise thereof and projecting across a side wall of an intermediate sash guide toward the sash member in the adjacent guide channel to engage a horizontal rail

15

9. A storm sash and screen assembly comprising a sash carrying frame of generally rectangular shape and including opposed upright jamb portions connected at the top by a header portion and connected at the bottom by a sill portion forming a unitary frame structure, the opposed upright jamb portions exhibiting sash engaging jamb faces each defining three parallel closely adjacent upright sash guide channels, each upright jamb portion being formed of sheet metal bent into right angular form in sectional outline and exhibiting an outer face disposed normal to the sash engaging jamb face, said frame adapted to be positioned within the win-

30

dow opening having an outer casing thereabout and provided with an outer window stop, the outer face of the frame adapted to overlap and be secured to said casing about the window opening to support the sash engaging jamb face in spaced relation to the jamb face of the window opening and the outer window stop, and a strip extending lengthwise along the outer window stop closing the gap between said stop and the sash engaging jamb face of the frame.
